[57] CLAIM

The ornamental design for a carpet repair tool, substantially as shown and described.

DESCRIPTION

FIG. 1 is an isometric view of a carpet repair tool embodying our new design;

FIG. 2 is a top plan view of the carpet repair tool shown in FIG. 1;

FIG. 3 is a right end elevation view of the carpet repair tool shown in FIG. 1 (the left end elevation view is a mirror image of this right end elevation view);

FIG. 4 is a front elevation view of the carpet repair tool shown in FIG. 1 (the back elevation view is a mirror image of this front elevation view); and

FIG. 5 is a bottom plan view of the carpet repair tool shown in FIG. 1.

FIG. 1.

FIG. 2.

FIG. 4.

FIG. 3.

FIG. 5.
